UNITED STATES PATENT OFFICE.

EDWARD B. HESS, OF NEW YORK, N. Y., ASSIGNOR TO ROYAL TYPEWRITER COMPANY, INC., OF NEW YORK, N. Y., A CORPORATION OF NEW YORK.

DESIGN FOR A TYPEWRITER FRAME.

Application filed September 14, 1925. Serial No. 14,779. Term of patent 14 years.

To all whom it may concern:

Be it known that I, EDWARD B. HESS, a citizen of the United States, residing in New York, county and State of New York, have invented a new, original, and ornamental Design for Typewriter Frames, of which the following is a specification, reference being had to the accompanying drawing, forming part thereof.

The figure is a perspective view of a typewriter frame showing my design.

I claim:

The ornamental design for a typewriter frame, substantially as shown.

EDWARD B. HESS.
